UNITED STATES PATENT OFFICE.

HARRY R. ATWATER AND CARL P. EICHLER, OF CLEVELAND, OHIO.

SINK-CLEANER.

SPECIFICATION forming part of Letters Patent No. 574,872, dated January 12, 1897.

Application filed January 2, 1896. Serial No. 574,014. (No model.)

To all whom it may concern:

Be it known that we, HARRY R. ATWATER and CARL P. EICHLER, citizens of the United States, and residents of Cleveland, county of 5 Cuyahoga, and State of Ohio, have invented certain new and useful Improvements in Sink-Cleaners, of which the following is a specification, the principle of the invention being herein explained and the best mode in 10 which we have contemplated applying that principle, so as to distinguish it from other inventions.

In the annexed drawings, Figure I is a top plan view of our improved sink-cleaner. 15 Fig. II is a bottom plan view. Fig. III is a cross-sectional view taken on the line 3 3 of Fig. I.

The sink-cleaner is formed from sheet metal; and it consists of the triangular blade 20 A, whose side edges extend forward from the rear and converge in straight lines to form the front end of the cleaner. The rear portion of the blade is formed with the upwardly-inclined edge a, and the handle A' is made 25 integral with such edge. One side edge a' of the blade is formed downwardly inclined and carries the brush B, such brush being secured to said edge by the socket b, riveted to said edge. The central portion of the blade 30 is formed with the longitudinal depression c,

so that from the latter the two side edge portions of the blade respectively incline upwardly and outwardly. The front end d of the blade is thus made triangularly pointed.

Other modes of applying the principle of 35 our invention may be employed for the mode herein explained. Change may therefore be made as regards the mechanism thus disclosed, provided the principles of construction set forth in the following claim are employed.

We therefore particularly point out and distinctly claim as our invention—

The herein-described sink-cleaner, consisting of the triangular blade A having the upwardly-inclined rear edge a integral with the handle A', the downwardly-inclined side edge a' carrying the brush B in socket b, the central longitudinal depression c, and the triangular-pointed front end d, substantially as 45 set forth.

In testimony that we claim the foregoing to be our invention we have hereunto set our hands this 31st day of December, A. D. 1895.

HARRY R. ATWATER.
CARL P. EICHLER.
